UNITED STATES PATENT OFFICE.

CHARLES S. MACKEARNIN, OF BOSTON, MASSACHUSETTS.

STATION-INDICATOR.

1,099,386.

Specification of Letters Patent. Patented June 9, 1914.

Application filed April 21, 1909. Serial No. 491,385.

To all whom it may concern:

Be it known that I, CHARLES S. MACKEARNIN, a citizen of the United States, residing at Boston, in the county of Suffolk and State of Massachusetts, have invented 5 certain new and useful Improvements in Station-Indicators, of which the following is a specification.

This invention relates to indicators for 10 passenger cars and the like and more particularly to electrically controlled indicators.

The primary object of my invention is to provide a construction of this class which can be operated at the will of the conductor or trainman and in which the indicating band may be reversed when desired. 15

Another object is to provide an indicator which may be suspended from the center of the top of the car and in which the street indications will appear upon both sides thereof. 20

Another object is to provide an improved construction of mounting for the sign carrying rollers or cylinders whereby they may be readily removed when desired. 25

A further object is to provide a new and novel mechanism whereby rotary movement may be intermittently imparted to the rollers. 30

A still further object is to provide a suitable system of transmission gearing by 35 means of which power is taken from the motor shaft and utilized to revolve the rollers.

With these and other objects in view, the present invention consists in the combination 40 and arrangement of parts, to be hereinafter more fully described and particularly pointed out in the appended claim, it being understood that changes in the specific structure shown and described may be made within the scope of the claim without departing from the spirit of the invention. 45

In the drawings forming a part of this specification, and in which like numerals of reference indicate similar parts in the several views, Figure 1 is a side elevation of my improved indicator showing the same secured to the roof of a railway car, Fig. 2 is a similar view, the side of the casing being removed, Fig. 3 is a transverse section on the line 3—3, of Fig. 2, Fig. 4 is an end elevation, the casing being shown in section, Fig. 5 is a detailed perspective view of the starting or stopping mechanism, Fig. 6 is a similar view of one end of the locking bolt, Fig. 7 is an enlarged detailed perspective view showing the coupling employed be-

tween the rollers and the operating shaft. Fig. 8 is a detail sectional view of one end of the detachable shaft. Fig. 9 is a diagrammatic view showing the manner in 60 which the circuit is controlled for operating the several parts.

Referring to the drawings, 1 indicates a substantially rectangular casing, in which are suitably secured the skeleton frame 65 plates 2. In these plates are mounted the motor shaft 3 and the roller shafts 4 and 5 on either side of the shaft 3. The ends of the latter shafts are provided with sleeves 6 which are tubular for the greater portion of 70 their length, and in which are provided longitudinally extending, diametrically opposed slots 8. The sleeves 6 are adjustable upon the shafts 4 and 5 and may be secured in their adjusted positions by means of the 75 set screws 7. Rollers 9 of substantially the same diameter as the shafts 4 and 5, are provided with lugs or trunnions 11 which engage in the slots 8. Upon the rollers 9 are endless transparent bands 12 upon which 80 are printed the names of the streets or other designating characters. These bands are securely held against any horizontal movement by the shoulders 10' formed in the ends of the rolls by the enlargements 10. 85

In one end of the casing I provide a reversible electric motor 13, from which the shaft 3 extends throughout the entire length of the casing and carries at its end the worm 14, which meshes with the worm gears 15, 90 horizontally disposed upon the shafts 16 mounted in bearings 16' secured to the frame plate 2. At either end of the shaft 16 are secured the beveled gears 17 which mesh with similar gears 18 secured to the 95 longitudinal shafts 4 and 5, to the ends of which as previously described are coupled the rollers 9.

Upon the operation of the motor, motion will be transmitted through the train of 100 gears and a rotary movement thus imparted to said rollers. At one side of the band 12 and adapted to rotate with the rollers, are secured upon the shafts 4 and 5 the spools 19, to which either end of a perforated tape 105 20 is attached, which moves over guide rollers 21 suitably supported upon the frame plate 2. Supported upon one of the frame plates 2 is a suitable box or receptacle 22 adapted to contain the electromagnet 23. 110 Extending inwardly toward the center of the casing is the bracket 24 provided with

bearings 25, in which is mounted the reciprocating locking bolt 26. The outer end of this locking bolt carries the contact plate 27 which is disposed within the receptacle 22 and is adapted to be retracted by the magnets 23 when the circuit is completed. Between the bearings 25 and surrounding the bolt 26 is a spiral spring 28 which returns the bolt to its normal position when the current is broken. Secured upon an insulating collar 29 is one contact member 30 of a knife switch, the other member 31 being formed upon one of the bearings 25. These switch points are in insulated sections and are provided with binding posts 32 and 32' respectively. Extending from the binding post 32' is a wire 33' leading to the ground or other suitable source of return, and from the binding post 32 extends the wire 33 leading to one leg of the reversing switch 37. In the outer end of the locking bolt 26 is mounted a roller 34 which is designed to bear against the tape 20 and hold the switch closed. An extension 35 is formed upon one of the plates 2 and surrounds the shaft 3, the extension having a face plate provided with a socket, which socket is arranged to receive the end of the bolt 26 when one of the perforations in the tape registers therewith thus breaking the circuit and stopping the motor. Located at any suitable points upon the car and in convenient reach of the conductor or trainman is the reversing switch 37, and arranged in the upper end of the switch is a push button 38. Leading from the push button to the magnets 23 is a wire 38', and connecting the magnets 23 with the ground or other source of return is the wire 38''. Leading from one of the legs of the switch 37 and connecting the same with a battery or any other suitable electric source of power is the wire A, and the wire 33 connects the other leg of the switch with the ground or other suitable source of return. Positioned at one side of the switch 37 are contacts 39' and 40 for closing a circuit to run the motor 13 in one direction, and arranged at the other side of the switch are contacts 39 and 40' for closing a circuit to run the motor in the reverse direction.

As before stated the motor 13 employed is of such a design as to be reversed in action when the current of electricity is imparted thereto, in two different directions, and as clearly shown in Fig. 9 of the drawings the switch lever 37 is pivotally connected and to one leg of it is attached the main feed supply wire A connected to any suitable source of power. By depressing the push button 38 while the lever 37 is in the position as shown in Fig. 9, the electromagnet will be energized and withdraw the bolt 26 from its engaging position with the tape in a manner previously described, after which the

switch lever is turned in either direction or in contact with either of the contacts 39 and 40 depending entirely in which direction it is desired to rotate the electric motor. It will be understood that the switch 37 comprises two blades, one of which contacts with either 39 or 40, connecting such points with the terminal of wire 33, and the other of which is adapted to contact with either 39' or 40', connecting such points with the lead A. When the switch lever 37 is turned to the right (Fig. 9) to contact with the contact points 39' and 40, the current of electricity will pass from the main supply wire A to the lever 37 and to the line wire 39' to one pole of the motor, the current of electricity thus conducted passing through the connecting wire 40' to the switch 37 and thence through the wire 33 to the binding post 32 of the switch member 30 and to the other member 31 of the switch to the corresponding binding post 32' to the wire 33' to ground or other source of return, thus completing the circuit and causing the said motor to be rotated in one direction, it being observed that the contact members 30 and 31 have been previously brought in contact by the electromagnet. When it is desired to reverse the rotation of the motor 13, the switch lever 37 is brought into contact with the contact points 39 and 40', whereby the current of electricity is conducted to the opposite pole of the electric motor by the wire 40'' and passes from the motor by the wire 39'' to the switch 37 and through the wire 33 to the binding post 32 of the contacting members 30 and 31 and conducted to the ground wire 33' in a manner previously described.

While I have shown an indicator which may be suspended in the center of a car and observed from either side thereof, it will be understood that the same may be made so that the indications will appear upon but one side thereof, when it is desired to secure the same in either end of the car.

My improved indicator is simple in construction, extremely easy to operate, and positive in its action. The parts may be readily assembled and will withstand a great amount of wear, thus producing a device which will be of great commercial value and public benefit. Any approved means may be employed for securing the indicator in the car, and I have shown for this purpose the rods 41 extending vertically through the casing at each corner thereof, and provided at one of their ends with the securing nut 41'. The rods extended through any convenient portion of the car ceiling and the nuts 41' will securely sustain the indicator in position. The casing and frame plates would preferably be constructed of sheet metal and the other parts being of small proportions, a very light and compact construction is secured, the cost of man-

ufacture is also thereby reduced to a minimum.

And having thus described my said invention, what I claim as new and desire to secure by United States Letters Patent is:—

An indicator of the class described comprising a pair of rollers, an indicating band adapted to be alternately wound on and unwound from said rollers, a reversible electric 10 motor connected to operate said rollers, motor circuits connected with a suitable source of electrical energy for supplying current to said motor, a hand controlled reversing switch for controlling said circuits, a tape 15 connected to move in synchronism with said indicating band and having perforations at

intervals, a spring-pressed bolt adapted to enter said perforations, a switch included in said motor circuits and having its movable member connected to said bolt, an electromagnet for retracting said bolt, a circuit including a source of electric energy for energizing said magnet, and a push button carried by the reversing switch and included in said last named circuit, substantially as de- 20 25 scribed.

In testimony whereof I affix my signature, in presence of two witnesses.

CHARLES S. MACKEARNIN. [L. s.]
